UNITED STATES PATENT OFFICE.

WILLIE D. WHITNEY, OF HOLLEY, NEW YORK.

HARROW-TOOTH FASTENER.

SPECIFICATION forming part of Letters Patent No. 728,347, dated May 19, 1903.

Application filed February 3, 1903. Serial No. 141,734. (No model.)

To all whom it may concern:

Be it known that I, WILLIE D. WHITNEY, a citizen of the United States, residing at Holley, in the county of Orleans and State of New York, have invented a new and useful Harrow-Tooth Fastener, of which the following is a specification.

This invention relates to fastening devices for harrow-teeth, and especially to devices for connecting points with the tooth-bars of spring-toothed harrows.

My invention has for its object to provide a fastener of this class by means of which the point, which in this case is a reversible point, may be clamped firmly and securely upon the harrow-tooth bar in such a manner as to enable it to be readily detached and reversed.

My invention further has for an object to provide a fastening device in which the point shall be held securely against vertical displacement.

Another object of my invention is to provide a fastening device in the form of a trapezoidal clip having a set-screw which requires to be but slightly loosened in order to permit the point to be swung to a diagonal position in the clip in order to enable it to be removed from the latter.

With these and other objects in view my invention consists in the improved construction, arrangement, and combination of parts which will be hereinafter fully described, and particularly pointed out in the claims.

In the accompanying drawings, Figure 1 is a central vertical section of one end of a spring-tooth having a double point connected therewith by my improved attaching means. Fig. 2 is a perspective view of the point and the securing-clip or attaching means. Fig. 3 is a central transverse section through the clip, the tooth-bar, and the point. Fig. 4 is a detail view of the central portion of the point which is engaged by the clip.

Corresponding parts in the several figures are indicated by similar characters of reference.

T designates a harrow-tooth, P a double or reversible point, and C the clip or fastening device, of my invention. The point member P is provided with a transverse depression or recess 10, the bottom wall of which, 11, is cut away at 11^a at each end to form at the side

walls 12 12 opposite pairs of shoulders 13 13. Embracing the point and tooth is a closed or continuous clip C, having an engaging bar 14 of a proper size to substantially fill the recess 10, with its sides engaging the side walls 12. From this bar extend side pieces 15 16 of such width at their inner portion as to engage the shoulders 13. At their outer ends they may be narrowed in order to reduce weight, and they are joined by a connecting-bar 17, which has a thickened portion forming a boss 17^a, through which extends a threaded perforation in which is fitted a set-screw 18. The side bar 16 is shown of greater length than its companion 15, giving the connecting-bar an inclined position, whereby the clip is made of substantially trapezoidal form, and said connecting-bar being in this manner diagonally disposed is of sufficient length to permit the point member P when the set-screw is loosened to be disposed diagonally and drawn freely from the clip, the diagonal dimension of the clip along the connecting-bar being necessarily sufficient to permit the longitudinal removal of a point having a somewhat-enlarged end, as is illustrated.

In operation the clip is passed over the point, so that the outer wall of the recess 10 rests against the engaging bar 14 of the clip, and the set-screw is then forced against the tooth to secure it and the point together.

It will be seen that by the construction herein shown and specified a very light and durable fastening device is provided whereby a harrow-point may be secured very firmly in operative position upon a harrow spring-tooth. By the trapezoidal shape of the clip material may be saved in the construction and the surface upon which dirt may lodge is reduced. Another important advantage of the trapezoidal clip resides in the fact that owing to the oblique disposition of the rear bar of said clip the portion of the set-screw lying between said rear bar and the tooth member T, against which said set-screw presses, is greatly reduced. It will be readily understood that if the clip were made rectangular instead of trapezoidal a much longer portion of the set-screw would be exposed, thereby weakening the construction and making the parts more liable to become loosened and separated from each other than where,

as by my present invention, the rear bar of the clip is obliquely disposed, rendering the device equally efficient to permit the removal of the point to be effected, but disposing one 5 end of the rear cross-bar so much closer to the engaging front bar as to much reduce the length of the portion of the screw disposed between the rear cross-bar of the clip and the harrow-tooth engaged by the point of the said 10 screw. The thickened portion of the obliquely-disposed bar 17 is an incidental feature which affords a very substantial support for the set-screw, which is seated in the threaded perforation extending through said thickened portion. The general construction is 15 one of extreme simplicity, and my improved fastening device is one which will readily commend itself to the users of an article of this kind.

20 Having thus described my invention, I claim—

1. The combination with a harrow-tooth and a point to be attached thereto, of a clip having a cross-bar engaging said point, side bars 25 of unequal length, a cross-bar connecting said

side bars, and a set-screw extending through said cross-bar and engaging the harrow-tooth.

2. The combination with a harrow-tooth and a point to be seated thereon, of a clip having a cross-bar engaging said point, side bars of 30 unequal length, a cross-bar connecting said side bars and having a thickened portion forming a boss through which extends a threaded perforation, and a set-screw extending through said perforation and engaging 35 the harrow-tooth.

3. The combination with a harrow-tooth, of a point therefor, provided at each side with a recess forming shoulders, a closed clip encircling the point and coacting with the 40 shoulders at both sides of said point, and a set-screw threaded through the clip and engaging the tooth.

In testimony that I claim the foregoing as my own I have hereunto affixed my signature in the presence of two witnesses.

WILLIE D. WHITNEY.
